(57) **CLAIM**

The ornamental design for a power tool and housing as shown and described.

DESCRIPTION

FIG. 1 is a first perspective view of a power tool and housing, according to an embodiment of the invention; FIG. 2 is a second perspective view of the power tool and housing of FIG. 1;

FIG. 3 is a front side view of the power tool and housing of FIG. 1;

FIG. 4 is a rear side view of the power tool and housing of FIG. 1;

FIG. 5 is a first side view of the power tool and housing of FIG. 1;

FIG. 6 is a second side view of the power tool and housing of FIG. 1;

FIG. 7 is a top side view of the power tool and housing of FIG. 1; and,

FIG. 8 is a bottom side view of the power tool and housing of FIG. 1.

Any components in the appended drawings shown in broken lines are for illustrative purposes only and form no part of the claimed design or a specified embodiment thereof.

1 Claim, 8 Drawing Sheets
